UNITED STATES PATENT OFFICE.

WILLIAM G. WILLIAMS, OF ELGIN, ILLINOIS, ASSIGNOR TO THE WILLIAMS MFG. CO., INC., OF ELGIN, ILLINOIS, A CORPORATION OF ILLINOIS.

TILTABLE CHIROPRACTIC TABLE.

Application filed July 18, 1921. Serial No. 485,669.

To all whom it may concern:

Be it known that I, WILLIAM G. WILLIAMS, citizen of the United States, residing at Elgin, in the county of Kane and State of Illinois, have invented certain new and useful Improvements in Tilttable Chiropractic Tables; and I hereby declare that the following is a full, clear, and exact description thereof, reference being had to the accompanying drawings, which form part of this specification.

This invention is an improvement in chiropractic tables of the type shown in my Patent No. 1,269,354, dated June 11, 1918, whereby the patient can be comfortably lowered from a standing to a horizontal position when being placed upon the table, and can be raised to a vertical position after being operated upon.

The invention provides novel means for raising the table frame when a patient is to be placed thereon, and for cushioning the lowering of the table frame with a patient thereon; to provide novel means whereby the tension of the springs for raising and for cushioning the lowering of the table frame can be regulated; to provide novel means for regulating the auxiliary spring means to operate when the table frame is being lowered with a patient; to provide an adjustable abdominal supporting cushion which may be either held rigid or can be yieldingly supported with more or less resistance by suitable springs; to provide novel means for adjusting the leg cushion; and to provide novel means for adjusting the head cushion to any desired angle.

Other minor objects and novel features of the invention will be hereinafter set forth.

I will explain the invention with reference to the accompanying drawings which illustrate one practical chiropractic table embodying the invention and will enable others to fully understand the invention and adapt and use the same, but I do not consider the invention restricted to the arrangement of parts illustrated in the drawings and therefore refer to the appended claims for summaries of the essentials of the invention, and the novel features of construction and novel combination of parts therein, for all of which protection is desired.

In said drawings:

Fig. 1 is a side elevation of the complete

table showing the table frame in lowered position in full lines, and indicating it partly raised in dotted lines.

Fig. 2 is a top plan view of Fig. 1, with the various cushions removed, but indicated in dotted lines.

Fig. 3 is a bottom view of the base showing the arrangement for the springs and their adjusting and controlling device.

Fig. 4 is a longitudinal section through Fig. 3.

Fig. 5 is an enlarged detail section partly broken away.

Fig. 6 is a section on the line 6—6 Fig. 3.

Fig. 7 is a section on the line 7—7 Fig. 3.

Fig. 8 is a detail section on the line 8—8 Fig. 5.

Fig. 9 is an enlarged detail view of the yoke 2.

Fig. 10 is an enlarged detail view of the hand wheel 3^w.

Fig. 11 is an enlarged view showing the means for adjusting and supporting the abdominal cushion and head, breast and leg cushions.

Fig. 12 is a detail view of shaft 28^a and parts mounted thereon.

Fig. 13 is a detail section on line 13—13 Fig. 11.

As shown in the drawings the table comprises a lower supporting or base portion and an upper adjustable table portion which as a whole is hingedly mounted upon the base so that it can be swung from a substantially vertical to a horizontal position and vice versa to facilitate the patient's getting upon or off of the table.

The base portion as shown is preferably formed of a casting 1 having depending flanges 1^a on its side and around one end, and provided with sockets at its opposite ends for the reception of suitable foot pads 1^b. This base is provided adjacent one end and between the side flanges 1^a with a cross bar 1^c which is provided with a horizontal opening for the reception of an externally threaded tube 2 on which is a nut 2^a by which the position of the tube in the bar 1^c may be regulated. Through this tube 2 extends a slidable rod or bar 3 which extends longitudinally of the base and has one end supported in the tube 2 and its other end supported in a bracket or lug 1^e depending from the base near the outer end thereof. The other end of the bar 3 may be reduced 110

or provided with a rod 3^a which extends through an opening in the outer end of the frame, and by which the bar 3 may be turned in the tube 2. A spring 3^b is strung 5 on the reduced portion or member 3^a of the bar 3 between the adjacent end of the bar 3 and the flange of the base, said spring normally tending to project the bar 3 toward the lug 1^e for a purpose hereinafter explained.

Mounted upon the tube 2 is a yoke 2^c threaded to the sleeve so that the position of this yoke relative to the bar 1^e can be adjusted by turning the tube so as to screw 15 the yoke toward or away from the bracket 1^e, and its position can be further adjusted by adjusting the tube longitudinally in the bracket 1^e by the nut 2^a. This yoke 2^c has laterally projecting arms 2^e, 2^d to which are 20 connected the inner ends of major helical springs 4 the other ends of which are attached to a transverse rod 6^a on the lower end of the table frame hereinafter referred to, and normally tends to hold the table 25 frame in upright position indicated in dotted lines in Fig. 1. The yoke 2^c may be fastened to the tube by any suitable means to prevent it turning thereon.

Mounted upon the bar 3 is a slide 5 which 30 is provided with laterally projecting arms 5^a to which are connected supplemental helical springs 4^a which extend parallel with the major springs 4 and are connected to the rod 6^d of the table frame. The slide 5 pref- 35 erably has a depending portion 5^b which is perforated for the passage of a guide rod 5^c which lies parallel with the bar 3 and has one end fastened to a depending bracket 1^e on the base by a set screw and its other end 40 extends thru the depending portion 5^b of slide 5 and is supported in an opening 2^t in the lower side of the yoke 2^c (see Figs. 3, 4, 8 and 9). The slide 5 is provided with a dog or pawl 5^e which is adapted to engage 45 any one of three notches 3^e, 3^f or 3^g in the bar 3 to arrest the movement of the slide away from the bar 1^e. The dog 5^e drops into one of the notches in the bar 3 according to the rotatorial adjustment of this bar. 50 The notches 3^e, 3^f, 3^g are successively spaced 90° apart around the circumference of the bar and also spaced apart longitudinally of the bar. The bar 3 can be turned by a hand wheel 3^w on the outer end of the rod 3^a so as to bring the plain side of the bar 3 or any one of the notches 3^e, 3^f, 3^g, therein uppermost in position to be engaged by the pawl 5^e, and thus control the operation of the supplemental springs 4^a as hereinafter explained.

If the bar 3 be turned with the plain side of the bar uppermost then the supplemental springs remain wholly inactive during the raising and lowering of the table. If the bar be turned so that notch 3^e is uppermost

the dog will drop into the notch when the table is fully raised to upright position and when the table is lowered the supplemental springs 4^a will coact with the major springs 4 in cushioning the lowering of the table 75 and aid in returning the same to upright position. If the bar is shifted so that the pawl would engage notch 3^f, the supplemental springs 4^a would come into action after the table is partly lowered and will assist 75 the major springs in returning the table to partly raised position. When the rod is shifted so that notch 3^g comes into position, the supplemental springs will come still later into action and go earlier out of action. 80

As stated when the plain side of bar 3 is uppermost the supplemental springs remain out of action. Of course additional notches may be provided if desired to give a greater variety of adjustment to the supplemental 85 springs, as may be desired by the operator, but for practical purposes three adjustments are sufficient.

The wheel 3^w may be provided with 4 radial arms designated as 1, 2, 3, 4 (see Fig. 90 10) and this wheel is fixedly attached to the rod 3^a and when arm #1 is uppermost the rod will be adjusted so that pawl 5^e would engage notch 3^e. When arm #2 is uppermost the pawl would engage notch 3^f and arm #3 is uppermost the dog would engage notch 3^g; and when arm #4 is uppermost the plain side of the rod 3 would be next to the pawl and it would remain ineffective. The wheel 3^w may be of any desired form: 95 and may be set so that the numerals will bear any desired relation to the plain side and notches of the bar 3. The uppermost arm of the wheel 3^w is adapted to engage a plate 3^v attached to the base (see Figs. 1, 100 and 2) and be yieldingly held in engagement therewith by the action of the spring 3^b, such spring being under slight compression and the bar 3 moved slightly forward endwise when the hand wheel 3^w is turned. 105

An expansion helical spring 3^s is strung on bar 3 between the bracket 1^e and the slide 5 and returns the slide and supplemental springs to their initial position when the table is raised to its upright position. This spring 3^s aids the main springs at all times except when the auxiliary springs come into play. The supplemental springs 4^a are of much greater strength than the spring 3^s so that the latter aids the main springs until 115 the auxiliary springs come into action. The auxiliary springs are depended upon to supplement the action of the major springs to accommodate patients of different weights. 120

The end of the base frame adjacent the bracket 1^e and farthest removed from the hand wheel 3^w is provided with opposite up-standing short curved standards 1^s (see Figs. 1 and 2) which support the through shaft 1^t upon which the table portion is pivotally 130

suspended. The table portion has a supporting frame consisting of parallel side bars or tubes 6 which are connected at one end by a casting 6^a and adjacent their other ends are connected to hangers 6^b hung upon the shaft 1^c. To the bars 6 adjacent hangers 6^b are attached depending arms 6^c to the lower ends of which is fastened the rod 6^d to which the springs 4 and 4^a are connected. When 10 the springs throw the table to upright position (as indicated in dotted lines Fig. 1) the arms 6^c engage stops or bumpers 1^e on the base frame (see Fig. 3 and 4) and limit the raising movement of the table.

15 The end casting 6^a of the table frame has a lug 6^f which is adapted to be engaged by a catch 7 pivotally mounted on the base, (see Figs. 1 and 4). This catch has an arm 7^a which depends through an opening in the base and is positioned to one side of the rod 3^a and is connected with the base by a spring 7^b (see Fig. 4) which normally tends to throw the catch into position to automatically engage the lug 6^f when the frame is lowered and hold the table in lowered position until the catch is disengaged. When 20 the catch is disengaged the table frame is automatically swung upwardly by the springs 4, hereinbefore referred to.

25 The table as shown has four cushion sections A, B, C, D. The head, chest and abdomen sections (A, B, C) are mounted so as to be adjustable longitudinally of the frame to suit different heights or lengths 30 of patients and are also capable of being adjusted to other positions relative to the table frame. The head cushion A may be constructed substantially as shown in my application filed December 11, 1920, Serial 35 No. 429,962. As shown herein it is supported on swingable bars 8 pivotally mounted on a shaft or rod 28^c in the upper ends of standards 28, the lower ends of which are provided with sleeves 28^s (see Fig. 11)

40 slidably mounted upon rods 27 above and parallel with the side bars 6 of the frame. Bars 27 are supported at their inner ends by castings 26 attached to the side bars 6, and at their outer ends are secured to lugs 45 25 on the casting 6^a. The sleeve 28^s may be locked to the bars 27 by a hand screw 28^b, or other suitable means.

The standards 28 are connected by the rod 28^c and by transverse tie rod 28^a just 50 above the sleeves and is secured to the standards by inner nuts 28^t and outer nuts 28^u.

55 The cushion A can be supported at any desired inclination by suitable means. As 60 shown a rod 30^c is pivotally connected to the table and telescopes into the upper end of a sleeve 30 which is hinged on the rod 28^a. The upper end of sleeve 30 is split, as at 30^t, and is provided at opposite sides with lugs 65 30^c having threaded openings which are en-

gaged by the threaded end of a bolt having a handle 30^t so that by turning this handle (see Fig. 1) the split end of the sleeve may be clamped upon rod 30^c to hold the same securely in any desired adjusted position. 70

A U-shaped member 29^a is hung upon the rod 28^a (Figs. 11 and 12) and provided with a transverse bore for the reception of a rod 29^c the bore being split at the inner side. The legs of the member 29^a loosely embrace 75 the end of sleeve 30. The member 29^a is held in position on the rod 28^a by a nut 29^b at one side and at the opposite side by the hub 29^s of a handle 29 which hub abuts against the nut 28^t. The opposed meeting faces of 80 the hub 29^s and the leg of the split member 29^a are cam surfaced so that by moving the handle 29 in one direction to rock the hub 29^s on rod 28^a the cam surfaces will engage and cause the member 29^a to tightly bind the 85 rod 29^c. By moving the handle in the other direction rod 29^c will be released.

The chest cushion B is connected to the rod 28^c by hinge members 60, and is normally supported by projections 28^u on the standards 28; the chest cushion will also be supported on the hinged bars 66, which are hinged on rod 28^c and carry the abdominal cushion C as described in my aforesaid application, when the chest cushion is sufficiently elevated to lift the cushion B off of the projections 28^u of the standards. 95

Hung upon the rod 28^c adjacent the arms 28 are two hanger straps 31, the lower ends of which are brought approximately close together and pivotally connected to the inner end of the rod 29^c. To the straps 31 near their lower ends are pivotally connected one end of a notched bar 32 the other end of which is connected to a slide 34 attached to the underside of cushion C (see Figs. 1 and 11).

100 Slidably mounted on the bar 32 is a slide 32^a having a catch 32^x adapted to engage the notches in the bar 32. This slide preferably has a bearing lug 32^z at one end which at all times engages the lower side of the bar 32; but when the catch 32^x is disengaged from the notches the slide 32^a can be moved along the bar 32. 110

To the slide 32^a are connected helical springs 32^b which are hung from the rod 28^c and are adapted to support the abdominal cushions yieldingly when the slide 34 is free to move on the rod 32. 120

The slide 34 carries a pawl 34^b which is adapted to engage notch 35^a in the rod 35 (as shown in Fig. 9) when the rod is turned to bring said notch uppermost. The shaft 35 can be turned so as to bring notch 35^a 125 uppermost to be engaged by the dog 34^b, or so that the notch 35^a will be at right angles from the dog then the dog 34^b would ride upon a smooth part of the bar 35, at which time the springs 32^b would yieldingly sup- 130

port the cushion as in Fig. 11. Rubber bumpers 35^c may be strung on the rods 35 to prevent jars when the cushion C is yieldingly supported by springs 32^b.

- 5 When shaft 35 is turned so that pawl 34^b can engage notch 35^a the cushion C will be supported rigidly in adjusted position by the bar 32, straps 31, and rod 29^c: When the dog 34^b engages notch 35^a the slide would 10 be up against the left hand bumper 35^c in Fig. 11. When the slide is free to move on shaft 35 the left hand bumper 35^c (Fig. 11), will limit the upward movement of the cushion C, and the right hand bumper 35^c 15 will limit the downward movement thereby.

While I prefer to use the abdominal cushion adjusting devices as shown no claim is made herein for such abdominal cushion adjusting devices as the same form the subject matter of a separate companion application.

The shaft 35 may be turned by any suitable means. As shown shaft 35 has a pin 35^d which is adapted to be engaged with an eye or loop in a rod 35^w which may be supported in openings in the hinge bars 66, carrying the cushion C, as shown in Figs. 1, 2, and 11. By drawing this rod right or left the pin 35^d would be swung right or left 25 and rock the shaft 35 accordingly.

The leg cushion D is also hingedly supported as described in my aforesaid application, but in lieu of the adjusting devices shown in said application a pin 9 is pivoted 30 to the frame supporting cushion D and depends through a split clamp member 9^a attached to the table frame 6 (see Figs. 1, 2, and 3) and provided with a screw shaft 9^b having a handle 9^c by which it can be turned. 40 When clamp 9^a is loosened the leg cushion D could be adjusted to any desired angle and then secured by tightening the clamp upon the pin 9.

It will be seen that the cushion C, can be 45 held in adjusted position either rigidly or yieldingly at the will of the operator as in my aforesaid application.

To assist the patient in getting on and off the table a foot rest is preferably provided.

50 As shown in Figs. 1 and 2, a foot rest 16 is connected to the adjacent ends of the side tubes 6 of the table frame.

Operation.

55 The operation of the various parts has been already explained in detail in connection with the description of such parts.

When a patient is to be placed upon the table, the catch 7 is disengaged allowing the 60 table frame to swing upwardly to approximately the position indicated in dotted lines in Fig. 1. The patient then steps upon the support 16 then the table frame is lowered with the patient to the position shown in 65 full lines in Fig. 1.

The major springs 4 hold the table normally in raised position, when released by the catch, and cushion the lowering of the table. The springs 4^a if used will come into play as above explained as the table is lowered. By shifting the point of engagement of the slide 5 with the bar 3 the time when the springs 4^a will come into action and the strength thereof can be varied, so that the operator can cause these springs to offer 70 more or less resistance to lowering of the table and more or less help in raising the table with patient thereon, according to the weight of the patient.

The relative inclinations of the leg, abdominal, chest and head cushions can be adjusted by the operator according to the treatment the patient is to have, the abdominal cushion can be locked rigidly in adjusted position by engaging the pawl 34^b with the 75 notch 35^a, or by turning this rod 35 to the position shown in Fig. 11 so the pawl will not engage it and the cushion will then be yieldingly supported by the springs 32^b as above described the tension of these springs 90 32^b and resistance of the cushion C to depression being regulable by adjusting the slide 32^a on bar 32.

The capability of the various parts for adjustment and the means for adjusting same, and the operation of the minor parts have all been hereinbefore clearly set forth. The advantages of the invention and utility of the table will be readily appreciated by chiropractors and physicians.

100 What I claim is:

1. In a table of the character specified, a base, a table pivoted thereon, major helical spring means connected to the table section, an adjustable member connected to the base section and to the major spring means, a member slidably mounted on the frame, and supplemental spring means connected with the table section and with said slidably member and means whereby the slidably member may be left free to slide or arrested to vary the point at which the supplemental springs will come into or out of effective operation.

2. In mechanism as set forth in claim 1, means for adjusting the tension of the major springs independently of the adjustment of the supplemental springs.

3. In mechanism as set forth in claim 1, a sleeve, and a yoke adjustably mounted on said sleeve and to which the major springs are attached, for adjusting the tension of the major springs independently of the adjustment of the supplemental springs.

4. In mechanism as set forth in claim 1, a bar having notches at different points in its length and at different points around its circumference, a sleeve to which the supplemental springs are attached slidably mounted on said bar, and devices on said sleeve

100

110

115

120

125

130

adapted to engage the notches of the bar, substantially as described.

5. In mechanism as set forth in claim 1, a rotatable bar having notches at different points of its length and at different points around its circumference, and a sleeve to which the supplemental springs are attached slidably mounted on said bar, said sleeve having a pawl adapted to engage with 10 that notch of the bar which may be brought into the path of the pawl by rotatorial adjustment of the bar.

6. In a table of the character specified, a supporting frame, a cushion supporting member hinged to the frame, and telescopic members respectively connected with the said member and with the supporting frame, one telescopic member having a split clamp 20 engaging the other telescopic member whereby the members may be locked together to regulate the inclination of the cushion supporting member.

7. In a table of the character specified a base section, a table section fitted thereon, 25 major helical spring means connected to the table section, an adjustable tabular sleeve connected to the base, a member on said sleeve connected to the major spring means, a bar, a sleeve slidably mounted on the bar, 30 supplemental spring means connected with the table section and with said slidably sleeve, and means whereby the slidable sleeve may be left free or arrested at various points on the bar to vary the point at which such 35 springs will come into or out of effective operation.

8. In mechanism as set forth in claim 7, means for adjusting the tension of the major springs independently of the adjustment of 40 the supplemental springs.

9. In mechanism as set forth in claim 7, said bar being rotatable and having notches at different points of its length and different points around its circumference, and said 45 sleeve having a pawl adapted to engage with that notch of the bar which may be brought into the path of the pawl by rotatorial adjustment of the bar.

10. In a table of the character specified, 50 a base section, a table section pivoted thereon, major spring means connecting the base and table sections, supplemental spring means connected with the table section, a rotatable longitudinally notched bar, and 55 a slide on said bar connected with the supplemental springs and adapted to vary the point at which such springs will come into

or go out of effective operation, substantially as described.

11. In mechanism as set forth in claim 60 10, said rotatable bar having notches at different points of its length and different points around its circumference, and said sleeve having a pawl adapted to engage with that notch of the bar which may be brought 65 into the path of the pawl by rotatorial adjustment of the bar, and means for preventing the sleeve rotating upon the bar.

12. In a table of the character specified, a frame, a cushion, a hinged member supporting the cushion and telescoping rod and sleeve members respectively connected with the hinged member and with the frame, the sleeve member having a split clamp engaging 70 the rod member whereby the members 75 may be locked together to adjust the inclination of the cushion, substantially as described.

13. In apparatus of the character specified, a frame, a cushion supporting member 80 hinged thereto, means whereby the cushion member may be rigidly yieldingly supported, a rod connected with said means, and a clamp engaging said rod whereby the members may be locked together to hold the 85 cushion in different adjusted positions.

14. In a table of the character specified, a hinged frame, a bar adjustably connected with this frame, swinging suspending links connected to the other end of said bar, 90 springs adjustably connected with the said bar for yieldingly supporting the cushions, a rod connected with the links, and a clamp for locking the said rod to hold the frame in adjusted position. 95

15. In an apparatus of the character specified, a hinged cushion, means for adjustably supporting the cushion, including a rod, a clamp engaging the rod having a cam face, and a handle having a cam portion 100 adapted to engage the cam face of the clamp, whereby the said clamp may be caused to bind upon or release the said rod.

16. In apparatus of the character specified, a hinged frame carrying a cushion, a 105 pin pivotally connected with the cushion, and a split clamp engaging said pin whereby the pin may be locked to hold the cushion in any desired adjusted position, and means for closing or releasing the clamp. 110

In testimony that I claim the foregoing as my own I affix my signature.

WILLIAM G. WILLIAMS.
